X-RAY CONTROL MEANS

Caperton B. Horsley, Gates Mills, and Edwin R. Goldfield, University Heights, Ohio, assignors to Picker X-Ray Corporation Waite Manufacturing Division, Inc., Cleveland, Ohio, a corporation of Ohio

Application March 11, 1937, Serial No. 130,296

2 Claims. (Cl. 250—34)

This invention relates to means for controlling the high tension circuit of an X-ray tube and the controlling means contemplated by the invention provides both compensation for variations in line voltage, and means for selectively operating the tube at any of the several kilovoltages which the technique of the apparatus demands.

Objects of the invention are to provide an extremely compact arrangement for the purpose, 10 adapted for use in a portable control unit for the tube served, and more particularly to provide but a single handle by which the operator may make both sets of adjustments, in an exceedingly simple manner.

15 The exact nature of this invention together with further objects and advantages thereof will be apparent from the following description taken in connection with the accompanying drawing, in which Fig. 1 is a diagrammatic view showing a 20 typical X-ray tube control circuit embodying the invention; Fig. 2 is a face view of the high tension circuit controller appearing in Fig. 1; and Fig. 3 illustrates in typical longitudinal section, a 25 physical embodiment of the controller switch means appearing in Fig. 1.

With reference now to the drawing, X is the X-ray tube which is to be served by the alternating current line L₁, L₂, the tube having for its filament control, a filament transformer FT and 30 filament control FC, and for its high tension circuit a high tension transformer HT, inverse voltage suppressor S, and exposure switch E. An input transformer IT is arranged to be effective between the line L₁, L₂, and the parts described, 35 and a voltmeter V and milliammeter MA are arranged in the circuit to serve the usual purposes.

What has thus far been described will be appreciated by one familiar with the art as generally typical of the latter, and it will be apparent 40 that the high tension circuit of the tube is controllable by control of the primary circuit of its high tension transformer HT.

The input transformer IT is conveniently an auto-transformer and a number of leads or taps 45 are provided for its windings, all as indicated in Fig. 1 of the drawing, wherein the leads are indicated as a series from 0 to 135.

The line L₁, L₂, being nominally at 110 volts but actually its voltage varying at times down to 50 say 105 and up to say 125 volts, we provide means effective between the line and the input transformer IT to adjust the transformer to the line. As here shown such means comprises a switch A connected on one side to the line L₂ as by the 55 connection a and having a number of points

marked 0 to 9, the switch being shown as upon the point 0 which is a dead point. The points 1, 4 and 7 are all connected to the 125 lead to the transformer IT, the points 2, 5 and 8 are connected to the 115 transformer lead and the points 3, 5 6 and 9 to the 105 lead.

Supposing the leads of the transformer IT to indicate relative turn units in the transformer winding, and the L₁ side of the line being connected to the transformer IT at the lead 50, it will 10 be apparent that when the switch A is on point 1, 4 or 7, the line will be effective across that portion of the transformer IT between its leads 125 and 50, which is 75 turn units. Similarly, when the switch A is on point 2, 5 or 8, the line 15 will be effective between the leads 115 and 50, or 65 turn units, and when the switch is on point 3, 6 or 9, the line will be effective between the leads 105 and 50, or 55 turn units.

As indicated in Fig. 1, one side of the primary 20 winding of the high tension tube transformer HT is connected to one end of the input transformer IT as by the line b in which are located the voltage suppressor S and exposed switch E. The opposite end of the high tension transformer primary winding is connected to a switch B which 25 controls its relation to the transformer IT. The switch B is preferably, according to our invention, physically connected with the switch A to move with the latter, but electrically insulated 30 therefrom, as indicated in Figs. 1 and 3. As to the physical relation of the parts, the switches are 35 preferably arranged for coaxial movement as indicated in Figs. 1 and 3 so that a single handle AB may be provided for coincident control of both 40 switches. In Fig. 3 the parts are shown as with the switch A on its point 2, the point 7 lying there opposite, and the switch B aligned with the 45 switch A.

The switch B is provided with three segmental 40 points including a point 123 so located that the switch B will be on this point when the switch A is on any of its points 1, 2 or 3, a second point 456 so located that it will be on this point when the switch A is on any of the points 4, 5 or 6, and a third point 789 so located that it will be on this point when the switch A is on any of its points 7, 8 or 9. The point 123 is connected to the 80 lead of the transformer IT, the point 456 to the 102 lead and the point 789 to the 135 or high end lead 50 of the transformer.

It will be apparent then that when the switch B is on its point 123, the high tension transformer HT will be served by 80 turn units of the transformer IT, when the switch B is on its point 55

456, 102 turn units of the transformer IT will be available, and when the switch B is on its point 789, the entire transformer IT with its 135 turn units will be available. Obviously, therefore, the three points of the switch B selectively provide for the high tension circuit of the tube, three different operating conditions for the tube, such that the tube may operate at any of three kilovolt ratings selected by the operator in the 10 usual manner according, for example, to the sections encountered in radiographic practice.

The face of the apparatus may be calibrated as indicated in Fig. 2, showing 10 points for the switch AB which, as here illustrated, is on its 0 15 point or "off" position. Corresponding to the points of the switch B, the face shows three ranges designated as "Low", "Medium" and "High". For each of these three ranges the corresponding three points of the A switch are indicated as 105, 20 115 and 125, in approximation of the actual voltages met in the nominal 110 volt line L_1, L_2 . The operator then, with the aid of the voltmeter V and knowing the desired kilovolts to be applied to the X-ray tube X, can easily select the proper 25 position for the switch AB which will thus by a single setting of a single handle, give him a close approximation to ideal control of the high tension circuit of the tube under the instant circumstances. It is understood that ordinarily in operation of the apparatus as a whole, the handle AB is properly set before closure of the switch E to 30 actually energize the tube.

What we claim is:

1. Means for controlling the high tension circuit of an X-ray tube from its supply line and comprising a transformer, primary switch means arranged to vary the relation of said line to said transformer, secondary switch means arranged to vary the relation of said transformer to said tube, an operator-operated control member, each of said switch means including a part connected to said control member for movement responsive thereto, and said switch means including contactors so arranged that for each relation established by one switch means a series of relations may be selected for the other switch means. 15

2. Means for controlling the high tension circuit of an X-ray tube from its supply line and comprising a transformer, primary switch means arranged to vary the relation of said line to said transformer, secondary switch means arranged to vary the relation of said transformer to said tube, said switch means including coaxially movable parts interconnected for their coincident operation as a unit, and said switch means including contactors so arranged that for each relation established by one switch means, a series of relations may be selected for the other switch means. 20 25
